LEADING-IN DEVICE FOR METALLIC
VACUUM-DISCHARGE CONTAINERS

Walter Dällenbach, Zurich, Switzerland

Application March 28, 1929, Serial No. 350,637
In Germany April 7, 1928

3 Claims. (Cl. 250—27.5)

This invention relates to leading-in devices for metallic vacuum-discharge containers.

The specification of my U. S. Patent Number 1,868,410 discloses a number of constructions of an insulating device which mechanically supports the conductor on the wall of the container. Among these there is one of particular importance in which the insulating supporting device is situated entirely outside the vacuum vessel, and the present invention has for one of its objects to improve that construction of leading-in device, and to protect as completely as possible from mechanical stresses the insulator which serves to seal the vacuum.

According to the invention the insulating supporting device engages the conductor near the place where the conductor passes through the wall of the container.

According to a feature of the invention, the insulating device concentrically surrounds the vacuum-sealing insulator and forms a liquid container in such a manner that the electric field tending to cause a flash-over on the outside of the vacuum-sealing insulator is situated in an insulating liquid, such as oil.

When the insulating supporting device comprises several parts, according to another feature of the invention the same is built up of several supporting insulators in the form of pillars arranged around the vacuum-sealing insulator.

According to a further feature of the invention, on the atmospheric side, the place of lowest potential difference between the conductor and metallic vacuum-vessel is placed so far from the vacuum-sealing insulator that the latter will not be endangered by flashing over.

Other features of the invention will be described hereinafter and pointed out in the claims.

Two embodiments of the invention are diagrammatically illustrated by way of example in the accompanying drawing wherein:—

Figure 1 is a vertical cross-sectional elevation showing one form of leading-in device according to the invention,

Fig. 2 is a transverse sectional view of the leading-in device shown in Fig. 1.

Fig. 3 is a vertical cross sectional view of a second form of the invention.

Figure 4 is a detail view, on an enlarged scale, of part of the device shown in Figure 3.

Like reference characters designate like parts throughout the several views.

Referring first to Figure 1, a leading-in conductor L having an electrode E passes through the wall of a metallic vacuum-vessel at S. This

vessel consists of two resilient tubular parts F, a vacuum-sealing insulator J between these parts F, and the wall W proper of the vessel. An insulating supporting device comprising a metal cap K, a metal flanged ring B, and insulators I₁ between these two members engages the conductor L at U near the place designated S where the conductor L passes through the wall of the vessel. Forces acting on the electrode E will be able to cause smaller displacements of the parts at S the nearer the point U is to S.

A plurality of supporting insulators I₁, for example three, are arranged around the insulator J as shown in Fig. 2. Sufficient space is provided between these insulators which latter are in the form of pillars for air to circulate about the surface of the insulator J and cool the leading-in device.

Referring to Figures 3 and 4, the yielding parts of the wall of the vessel shown in Figure 1, as resilient tubes are, in this construction, formed as diaphragms F₁ and F₂ of sheet metal. It is preferable to make the upper diaphragm F₁ double and the lower diaphragm F₂ single. For if the electrode holder is deflected from its vertical position through a small angle sideways by a force applied to the electrode, the axis of the insulator J will also be deflected through a small angle, owing to the lateral displacement of the point S, but in the opposite direction. The relative rotation of the axis of the parts L and J with respect to the electrode holder at S must therefore be taken up by the upper diaphragm F₁ while the lower diaphragm F₂ has only to take up the small angle through which the axis of the parts L and J is deflected relatively to the vertical. If the three single diaphragms have the same dimensions, they will be stressed in a similar manner during a lateral deflection of the electrode holder.

At N are situated welded joints or seams along which the diaphragms are connected with the extension tubes of the insulator J and with the wall of the vessel.

The place S where the upper diaphragm F₁ is connected to the leading-in conductor L is of particular interest and is shown enlarged in Figure 4. The conductor L has a collar or skirt K which may be welded along its free edge at N with the diaphragm F₁. Such welding should be effected with a small flame to avoid heating the entire conductor L and to obviate stresses which might occur in the seam N if the conductor L itself were welded directly to the diaphragm F₁.

One or more screens R_1 , R_2 may be attached to the wall W of the vessel for protecting the lower diaphragm F_2 from heat radiated by the electrode.

- 5 In this construction the members B , I , K form together with the wall W a receptacle which concentrically surrounds the vacuum-sealing insulator J and can be filled with an insulating liquid, e. g. oil, so that the electric field tending 10 to cause a flash over on the outside of the insulator is situated in this liquid, preferably oil. If the lengths of the creeping paths over the insulators J and I are not different, a flash over 15 will always occur on the outside of the insulator I , and the vacuum sealing insulator J is efficiently protected from the effects of such flashes. The insulating liquid may serve simultaneously for cooling the insulator J and the parts adjacent to it.
- 20 The same action can be obtained without the aid of an insulating liquid, particularly oil, by making the creeping paths over the insulators J and I sufficiently different in length, or, in general, by arranging that on the atmospheric side 25 the places of lowest flash-over potential-difference between the conductor L and the wall W of the metal vessel are placed so far from the vacuum-sealing insulator J that the latter will not be endangered by breakdowns of the di- 30 electric.

The above described advantages and the devices claimed hereinafter are independent of the position at which connection is made to the current supply. In general, the upper end of the 35 conductor L will be used for that purpose, but other parts which are in electrical connection with the electrode may serve for leading-in current, thus, for example, the upper tube which is hermetically connected with the insulator J may 40 be used.

I claim:—

1. In combination, a metallic vacuum discharge container including a wall constituted in

part by two metal parts and a vacuum-sealing insulator between said metal parts, a leading-in conductor passing through one of said wall parts, a device insulating and securing said conductor to said wall of the container, said device being located wholly outside the vacuum, and disposed concentric with said insulator, and engaging the conductor adjacent the point where the latter passes through the wall part and forming, together with the said insulator, a chamber containing an insulating liquid, in which the electric field tending to cause a flash-over on the outside 10 of the vacuum-sealing insulator is situated.

2. In combination, a metallic vacuum discharge container including a wall constituted in 15 part by two metal parts and an interposed vacuum-sealing insulator, one of said metal parts being in the form of a double diaphragm and the other part in the form of a single diaphragm, a leading-in conductor passing vacuum-tight 20 through said double diaphragm, and a device insulating and securing said conductor to said wall of the container, said device being located wholly outside the vacuum and engaging the conductor adjacent the point where the latter 25 passes through the double diaphragm.

3. In combination, a metallic vacuum discharge container including a wall constituted in part by two metallic diaphragms and an interposed vacuum-sealing insulator, a leading-in 30 conductor passing vacuum-tight through one of said diaphragms, the second diaphragm being situated between said insulator and an adjoining portion of the wall of the container, a device insulating and securing said conductor to 35 said wall of the container, said device being located wholly outside the vacuum and engaging the conductor adjacent the first mentioned diaphragm, and a screen arranged to protect that second mentioned diaphragm from the heat of 40 an electrode carried by said conductor.

WALTER DÄLLENBACH.
